UNITED STATES PATENT OFFICE.

ROYCE L. BEERS, OF DETROIT, MICHIGAN, ASSIGNOR, BY MESNE ASSIGNMENTS, TO RILEY STOKER CORPORATION, OF WORCESTER, MASSACHUSETTS, A CORPORATION OF MASSACHUSETTS.

TUYÈRE STRUCTURE FOR UNDERFEED STOKERS.

Original application filed June 16, 1922, Serial No. 568,797. Divided and this application filed August 16, 1922. Serial No. 657,684.

My present invention in tuyère structures has particularly to do, in some of its aspects, with stokers wherein a plurality of laterally extending retorts open into a longitudinal main retort at and below the top-margins of the retort castings, one form of such stoker being shown in my co-pending application Serial No. 568,797, filed June 16, 1922, of which this case is a division.

Among the objects of my invention are to provide a corner-tuyère structure for use as described, which has great strength, heat-resistivity, adequacy of air-distribution, simplicity and economy in initial construction, facility for renewal or replacement of damaged parts, and ability to function without substantial detriment to the operation of the stoker even when the tuyère structure is partially destroyed. Other and further objects will become apparent to those skilled in the art from the following disclosure.

To these ends my invention consists in the features of construction and combinations and arrangements of parts hereinafter more particularly described and claimed.

In the drawing Fig. 1 is a horizontal section through a stoker-equipped furnace, with parts broken away; Fig. 1^a is a fragmentary sectional view on the line a—a of Fig. 1. Fig. 2 is a vertical section through a corner post and tuyère structure, taken on line 2—2 of Figs. 1 and 3; Fig. 3 is a section on line 3—3 of Fig. 2; and Fig. 4 is a perspective view of the corner-tuyère structure.

As to the general construction of the stoker illustrated, it will be understood that green fuel from a supply hopper 10 is fed through a front-wall throat 11 into a main longitudinal retort 12 by the reciprocation of a suitable ram appropriately driven as by ram-engine 14, in known fashion. The green fuel thus fed into the main retort 12 is, in part, ultimately consumed in the combustion area directly above the main retort, but other portions of the fuel, (more or less affected by the passage through the main retort) will be distributed to lateral retorts 15 for consumption in the further area served by these retorts. Of these lateral retorts a suitable plurality may be provided, dependent on the length of the main retort and the de-

sired width of each lateral retort. The particular installation shown provides lateral retorts at one side only of the main retort, but of course my present invention is not restricted in this regard.

These several retort structures of course form part of a fire-box floor which as a whole extends from the front wall 17 to the bridge wall 18, and from one side wall 19 to the other side wall 20 of the boiler-setting, and it will of course be understood that, consistently with usual practice, air under pressure is admitted beneath the retorts for distribution through the tuyère-openings, generically indicated at 26, around the margins of the retort structure, to support combustion within the fire-box.

Since the lateral retorts open to the main retort at and below the upper margins of the retort-casting, a side-wall of the main retort 12 takes form as a series of posts 78, each such post comprising as its end surface a portion of the side wall of the main retort and as its two side surfaces respective portions of the side walls of two adjoining lateral retorts, the laterally-extending retorts being spaced apart somewhat to leave there-between air-trunks 83, each such air trunk being spanned by suitable tuyère blocks 82, which preferably are of plate form, disposed in generally upright arrangement side by side, to rest on the flanged side-margins of the retort-casting, and supplemented by corner-tuyère structures 84 forming the tops of the side wall posts. Such corner-tuyères especially form the subject of the present case.

Any corner tuyère employed at such a place in a stoker as described is especially subject to hard usage and to extreme conditions tending to its destruction. Constantly subjected to high temperatures, called upon to supply air adequately toward both branch retorts and toward the main retort, and in position subjecting them to coal-pressure due to the cross-currents of fuel flow in the longitudinal feeding of the fuel to the main retort and its diversion into the lateral retorts, these corner tuyères are called upon to act under very severe conditions, and their failure of operation is of especially serious detriment to the operation of the stoker.

In the corner tuyère structure shown I

provide a plurality of complementary thin sections, interlocking to give firm assembly and shaped in the aggregate to present in their upper portion a rounded contour, nearly quarter-spherical in extent, for exposure to the fire, with tuyère openings in all directions of such quarter spherical surface, these sections being shaped at their lower portions to make up a stem for insertion into the air-trunk space between two lateral retorts. In detail, five sections or layers are shown, although more or less may be used, these sections 84^a, 84^b, 84^c, 84^d and 84^e, having each a head portion (85^a to 85^e) and a stem portion (86^a to 86^e). Each section has a plate-web (87^a to 87^e) marginally bordered throughout the exposed head part by a flange-rim (88^a to 88^e) through which flanges the tuyère-openings 26 are made, each leading to an interspace between adjacent body webs, so that in the assembly the associated sections present a smooth exterior contour interrupted only by the said tuyère openings 26. The stem portions have interlocking and spacing lugs (89^a to 89e) formed as short edge-flanges thereon, to contact one with another for positioning the layers in assembled relation with the lower portions of the body webs substantially parallel, the positions of such lugs being preferably such that not only is a bottom-opening left free for ingress of air to the interspaces between the head-portions, but side openings may also be left between the webs of the longer sections. Preferably all of the stems will be notched, as at 90, immediately below the heads of the respective sections, for engagement with the flanges 78' marginally bordering the adjacent lateral retorts, such flanges preferably having therein notches 90' to facilitate insertion of the tuyère-sections in erection or replacement of the parts.

The surfaces of severance or cleavage between the layers or sections of the corner tuyère are preferably nearly parallel between the stem portions, but through the heads preferably sweep on curves of progressively shorter radius for uniform distribution of the tuyère openings and stronger interlock of the parts. Also it is preferred that the stem portions of the sections nearest the end or front of the posts may be short, and the stems of the sections more remote from that end shall be longer, for economy in construction, mechanical adequacy of anchorage and interlocking effect to resist the strain imposed on the heads of varying heights, and beneficial tendency toward apportionment of air distribution.

It will be observed that each tuyère section or layer provides a head portion of great ruggedness, integrally connected with its heat-conductive stem which will be constantly subjected to the cooling influence of

the air flowing through the relatively narrow or flat interspaces or channels, so that the heat-resistivity of the construction is great, and further that even should a portion of the corner tuyère be burned away, notwithstanding its heat-enduring construction, the stem-portions will themselves afford a grid which will uphold the fuel and afford a measurable directional distribution of the air, enabling the stoker to be continued in operation if necessary without excessive detriment to the stoker or creation of a hole in the fire. 75

While I have herein described in some detail a particular construction of particular advantage, for purposes of full disclosure, it will be understood by those skilled in the art that in its broader aspects my invention is not limited to the precise details shown and described, and that many changes in particular construction and arrangement of parts may be made without departure from the spirit of my invention within the scope of the appended claims. 80 85

I claim:

1. In an underfeed stoker, having a main retort with side openings separated by posts, and having lateral retorts communicating with said openings, and having between adjoining lateral retorts spaces constituting air trunks, a corner-tuyère structure for such a post comprising a plurality of sections jointly presenting a working surface of approximately quarter-spherical form, each of said sections comprising a head portion and a stem portion, and said sections providing air spaces between their stems and opening through said surface of the heads. 95 100

2. A multi-sectioned corner-tuyère structure for an underfeed stoker, comprising a plurality of sections each having a head portion to present a part of the working surface and a stem portion to extend into an air trunk, said head portions jointly presenting a working surface of approximately quarter-spherical form and having tuyère-openings between said sections. 105 110

3. A multi-sectioned corner-tuyère structure for an underfeed stoker, comprising a plurality of section each having a head portion to present a part of the working surface and a stem portion to extend into an air trunk, said head portions jointly presenting a curved working surface of approximately quarter-spherical form and having tuyère-openings between the sections, and said stem portions having open spaces between the sections to supply air to the tuyère-openings. 115 120

4. A multi-section corner-tuyère structure having a working surface of generally part-spherical curvature, and divided into sections on curved surfaces of cleavage which are respectively of different radii. 125

5. A multi-section corner-tuyère structure 130

having a working surface of generally parti-spherical curvature made up of interlocked sections having air openings therebetween.

5 6. Structure as set forth in claim 3, wherein the stems are of different lengths, increasing in length toward the discharge side of the stoker.

10 7. A multi-sectioned corner-tuyère structure having a working surface of approximately quarter-spherical form comprising a

plurality of sections each having a stem portion and a head portion, the surface of cleavage of the head portions non-aligning with the surfaces of cleavage of the stem portions. 15

8. Structure as set forth in claim 7 wherein in each two adjacent sections form an air passage therebetween, and adjacent heads are formed with supplemental notches to afford tuyère-openings communicating with 20 said air passages.

ROYCE L. BEERS.
